UNITED STATES PATENT OFFICE.

JOHN MATTINEN, OF BELLEFONTE, PENNSYLVANIA.

BOAT.

Application filed March 19, 1926, Serial No. 96,034. Renewed June 10, 1927.

This invention relates to boats, the general object being the provision of a board having buoyant members provided upon its opposite ends and fitted with both propulsion and steering apparatus and which may prove of great value as a life boat or afford a mechanical addition to the usual and conventional form or forms of surf boards.

With the above and other objects in view, the invention further includes the following novel features and details of construction, to be hereinafter more fully described, illustrated in the accompanying drawings, and pointed out in the appended claims.

In the drawings:

Figure 1 is a side elevation of the invention.

Figure 2 is a fragmentary longitudinal section taken through the board proper and illustrating the construction and arrangement of the propulsion apparatus.

Figure 3 is a top plan view of the invention.

Figure 4 is a vertical section taken on line 4-4 of Figure 1.

Figure 5 is a sectional view taken through a buoyant member and the supporting means therefor.

Referring to the drawings in detail, wherein like characters of reference denote corresponding parts, the reference character 10 indicates a board having enlarged end portions 11 and including semi-circular longitudinally split concave plates 12 having their meeting lower edges arranged in overlapping relation and secured to the upper side of the enlarged end portions adjacent the edges thereof. Their upper sides provide openings 13 therein through which air valves 14 may protrude from buoyant air filled tubes 15 housed within the compartments defined by the plates 12. Such tubes 15 serve to float a person or persons upon the board when submerged an appropriate depth within the water. The above entitled invention is primarily adapted for occupancy and operation of two persons, one upon each end for operating a propulsion steering apparatus, which will be presently apparent.

The propulsion apparatus consists of an operating lever 16 pivotally mounted off center upon the board and extends and adapted for oscillatory movement within an elongated slot 17 provided in the board. A relatively narrow board 18 suspended at its

outer end upon the under side of the board 10 and adjacent one end thereof through the instrumentality of a pivoted bar 19 is adapted for simultaneous operation with the lever 16 which in turn has its lower end pivoted within a bifurcated portion 20 defined within the forward end of the board 18. A multiplicity of plates or paddles 21 are pivotally mounted upon the under side of the board 18 and restricted as to pivotal movement in one direction by oppositely disposed plates 22 suspended from the under side of the board 18. Such plates or paddles 21 are adapted for operation and for relative pivotal swinging movement in the positions as clearly illustrated in Figures 1 and 2 of the drawings. Said plates 12 also serve as an enclosure or seat for the operators of the boat.

The steering apparatus consists of a steering post 23 set at an inclination and in an opposite direction with respect to the operating lever 16 in order that the latter may be easily manipulated upon the board 10. A spool 24 is mounted thereon and adapted for simultaneous rotation therewith. A rudder such as indicated at 25 provides a cutout portion 26 within its upper side for the reception of an appropriate portion of the enlarged end portion 11 of the board 10 and pivotally mounted upon the upper side thereof while a reduced elongated extension 27 extends beneath and longitudinally of the board and has the opposite ends of a cable 28 secured to its opposite sides. Said cable has its intermediate portion wrapped upon the spool 24 and its remaining length trained over grooved pulleys 29 positioned upon the under side of the particular enlarged end portion 11.

In the use and operation of the propulsion apparatus it is clearly apparent and manifest that the operator may be seated upon an enlarged end portion 11 of the board 10 and held against accidental displacement thereon through the instrumentality of the plates 12 housing the tube 15 while he may support and brace himself upon foot rests 30 suspended from the under side of the board 10, as may the person seated upon the opposed enlarged end 11 of the board 10. The oscillatory movement imparted to the board 18 by the operation of the lever 16 will allow the plates or paddles to rise and fall upon their pivots to thrust the water in an opposite direction.

with respect to the direction of travel pursued by the occupants of the boat.

It will thus be noted that the invention as previously described and illustrated affords an exceedingly useful and advantageous form of boat capable of being stored within a confined area upon vessels or transports to serve as a medium of life saving apparatus, seating two persons and offering propulsion and steering means therefor in order that the boat may leave the immediate vicinity of a sinking vessel, which creates a suction upon submerging and tends to draw the life boats and survivors downwardly therewith. The invention in addition provides a boat which may be used at water fronts and bathing beaches and which owing to the construction thereof may be manufactured in great numbers and sold at a very nominal cost.

The invention is susceptible of various changes in its form, proportions and minor details of construction, and the right is herein reserved to make such changes as properly fall within the scope of the appended claims.

Having thus described my invention, what is claimed is:

1. A boat comprising a board, buoyant members arranged upon its upper side and adjacent its opposite ends to prevent displacement of persons seated thereon, a rudder mounted for pivotal and lateral swinging movement upon the under side of the board, a steering post journaled upon the upper side of the board and connected with the rudder, and a propulsion apparatus mounted upon the under side of the board and having an operating lever connected therewith.
2. A boat comprising a board having semi-circular buoyant members secured to its upper side and adjacent its opposite ends to provide seats and prevent accidental displacement of persons seated upon the board,

a rudder mounted for lateral pivotal swinging movement upon the under side of the board and adjacent one end thereof, a steering post journaled within the upper side of the board adjacent one of the buoyant members and having a spool fixed thereto and receiving successive wrappings of a cable thereon which in turn having its opposite ends secured to the opposite sides and inner end of the rudder, an operating mechanism comprising a longitudinally movable plate suspended upon the under side of the board adjacent its opposite end, and a lever operable upon the upper side of the board and having its lower end connected with the aforementioned plate to impart the necessary momentum thereto.

3. A boat comprising a board having semi-circular buoyant members secured to its upper side and adjacent its opposite ends, a rudder mounted for pivotal lateral swinging movement upon the under side of the board and adjacent one end thereof, a steering post journaled upon the upper side of the board and having a spool fixed thereto upon which is wrapped the intermediate portions of a cable having its remaining length trained over pulleys mounted upon the under side of the board and having its ends connected with the opposite sides of the rudder, an operating mechanism comprising a relatively narrow plate suspended from the under side of the aforementioned board and having a plurality of spaced parallel pivotally mounted plates upon its under side, and an operating lever mounted for oscillatory movement within a slotted portion in the board and having its lower end connected with one end of the relatively narrow plate for imparting the necessary momentum thereto and to the plates suspended therefrom.

In testimony whereof I affix my signature.
JOHN MATTINEN.
